WALTER ADAM SMITH, OF BELVIDERE, ILLINOIS, ASSIGNOR TO NATIONAL SEWING MACHINE COMPANY, OF BELVIDERE, ILLINOIS, A CORPORATION OF ILLINOIS.

LATCH DEVICE.

Application filed July 6, 1926. Serial No. 120,697.

This invention relates to bib locking devices, intended more particularly for locking the bib device of a sewing machine cabinet; although it is not restricted to such use and 5 may be used in connection with typewriter cabinets, and otherwise.

In sewing machines, the operative mechanism is provided with a metal base plate pivotally or hingedly mounted at the margin of 10 an opening in the top of the cabinet and designed so that the mechanism may be swung below the surface of the cabinet when not in use, and may be raised to the surface of the table for use. To hold it in raised position, 15 the cabinet is provided with a hinged section of table top, commonly known in the trade as a bib. A portion of the machine base rests upon a portion of the bib, and when so positioned for operation, the motion of the machine parts produces considerable vibration, 20 whereby the bib is shaken and rattled.

In an attempt to remedy this objection, locking devices have been used on the base of the machine to lock said base to the bib. Such 25 locking devices may comprise a latch device to engage a suitable projection on the bib. Notwithstanding the use of a locking device between the machine base and bib, the vibratory motion of the machine parts produces 30 relative movement not only between the machine and the cabinet but also between the bib and the cabinet, which is detrimental to the sewing machine as a whole and unpleasant for the operator of the machine.

It is desirable, therefore, to provide, in addition to the base and bib latching device, a locking device between the bib and cabinet proper.

The principal object of my invention, 40 therefore, is to produce a device by which the bib will normally be unlocked from the cabinet, so as to be swingingly movable with respect to the cabinet table top, when the machine is being moved into and out of operative position; and which will be automatically operated into a position to lock the bib to the cabinet by the act of the machine base being brought into operative position upon the bib.

Another object of the invention is to pro-

vide a bib locking device which will be automatically actuated into its locked position by means upon the sewing machine base and which will automatically assume an unlocked position upon withdrawal of said means. 55

Another object of the invention is to provide a bib locking device so correlated in its position and in its action to a machine base locking device, as to supplement the action of each other, and which will operate simultaneously with the machine locking device in effecting the locking action between the bib and cabinet. 60

These and other objects of the invention will be more fully understood by reference to 65 the accompanying drawings in which I have shown one form of device embodying the principle of the invention.

In the drawings:

Figure 1 is a top or plan view of a sewing 70 machine in position upon the top of a cabinet, the latter being partially broken away, with the bib lock of my invention indicated in dotted lines.

Figure 2 is a vertical sectional view 75 through the bib of the sewing machine cabinet, with my locking device shown in elevation.

Figure 3 is a vertical sectional view 80 through the bib and the top of the cabinet table, with the machine base raised.

Figure 4 is a plan view of a portion of the table top and of the bib.

Figure 5 is a detail view, enlarged, showing the actuating member on the machine, 85 engaged with the locking bolts of the device; the bolts being in the unlocked position.

Figure 6 is a view similar to Figure 5, with the bolt ends spread apart or in locked position. 90

Referring to the drawings, A represents a sewing machine cabinet, in part, provided with a table top 1, which is centrally apertured as indicated at 2, whereby a machine base B hingedly secured along one of its side 95 margins to the table top 1, as indicated at 3, may be swung into a pocket 4 located below the table top 1, when the machine is not in use, and through which recess 2 the machine may be lifted out of the pocket and then 100

brought to proper operative position with relation to the table top, in a well known manner.

To the side of the aperture 2, opposite that 5 to which the sewing machine base is pivotally or hingedly mounted, is what is known in the trade as the bib C, which latter is likewise swingingly mounted so as to be raised above the surface of the table top 1 when the machine B is being lifted out of the pocket 4 and to swing downwardly into normal position with its top surface 5 in the same horizontal plane as the top surface 1 of the table, and there to engage the machine base B when 10 the latter is brought down into its operative position. The upper edge of the swinging bib C is rabbeted so as to form a shoulder support 6 for the edge 7 of the machine base B; the machine being thus held in its operative 15 position by the shoulder support 6 along one of its edges and by the hinged connection 3 along its opposite edge.

To lock the machine base and the bib C together, I provide on the lower side of the 20 bib, a flat bar or plate 8, the end of which projects beyond the inner edge 9 of the bib C, as clearly shown in Figures 3 and 4. Upon the machine base B I provide a swinging lever 10 pivotally mounted at 11 to the base 25 and carrying on one arm a latch 12 adapted for engagement with the bar 8. The lower edge of the latch 12 is curved so that when the machine B is being moved into operative 30 position, this rounded edge acts with the familiar latch action and its hook or shoulder portion 13 is brought into locking engagement with the bar 8, as clearly illustrated in Figures 35 and 6. A tension spring 14 keeps the latch lever 10 in proper operative position 35 when disengaged from the bar 8 and promptly returns it to that position as the hooked shoulder 13 is moved out from under the bar 8. This movement is accomplished by reason 40 of the fact that the short arm 15 of the lever 45 10 is pivotally attached at 16 to a vertically movable push button 17. The button 17 is mounted through the machine base B with its upper portion projecting so as to be in convenient position to be depressed by the operator 50 when the latter desires to disengage the hooked lever 10 from the bar 8. This is all familiar practice and my invention is not to be limited to the particular form or shape 55 of the means just described for locking the base to the bolt 8 on the bib.

Near this locking device, however, I secure 60 to a flange 18 on the machine base B, an actuating member 19, by means of a screw bolt 20, or any other convenient means. The function and purpose of this actuating member 19 will presently be described.

Upon the under surface 21 of the bib C, I provide a plurality of apertured bearing plates or members indicated at 22, the apertures thereof being in alignment and parallel

with the side edge 9 of the bib. These bearing plates 22 are spaced apart in groups, one group arranged to accommodate a bolt bar D and the other group to support a bolt E. The bolts D and E may be of any convenient form 70 in cross section but I prefer, and have herein shown these bolts to be square in cross section, as clearly indicated. It follows that the bearing openings in the supports 22 for these bolts must be complementally shaped so that 75 the bars or bolts D and E may be moved longitudinally through the bearing plates 22. As a matter of convenience, I have made the bolts D and E of different lengths but this is not essential to the invention, as will presently appear. The bolts D and E are bent 80 between their ends so as to present an inwardly turned arm 23 on the bar D and an arm 24 on the bar E. These arms 23 and 24 are spaced apart, are parallel to each other and 85 are sufficiently close together so that the lower portion of the actuating member 19 of the plate B, when the machine is being lowered into its operative position, will be entered 90 into the space between the two arms 23 and 24, and as the lowering continues, push further into said space and spread said arms 23 and 24 apart. This movement imparts a longitudinal movement to the bolts D and E, through their respective bearing plates 22, 95 and in opposite directions. Moreover, this movement of the bolts D and E will be of such extent as to cause the extreme end 25 of the bar D and the extreme end 26 of the bar 100 E to project beyond the respective side margins 27 and 28 of the bib C, as shown in Figure 2.

This spreading apart of the bolts D and E is accomplished, as will be understood by reference to Figures 5 and 6, by means of the actuating member 19, provided with converging side margins 29, which exert a wedging action between the two arms 23 and 24 to spread them apart. When so spread apart, the ends 25 and 26 of the bolts D and E, respectively, will engage the under side of the top 1 of table A and thus securely lock the bib C to the table A.

Surrounding the bolt D is a tension spring 115 30, one end of which bears against the surface of a bearing plate 22 and the other end against a pin 31 in the bolt D. Thus as the bolt D is moved outwardly the spring 30 is put under tension and as soon as the actuating member 19 is moved away from the arm 23 of said bolt, the spring 30 expands and promptly returns the bolt D to its original position shown in Figure 4. The bolt E is similarly provided with a spring 32, one end of which bears against the pin 33 on the bolt E and the other end of which bears against the bearing plate 22. The action of the bolt E and spring 32 is the same as just explained with reference to the bolt D and spring 30.

To prevent the springs 30 and 32 from driv-

ing the bolts D and E from their locked position, as shown in Figure 2, beyond their properly unlocked position as shown in Figure 4, the bolt D is provided with a stop pin 34 adapted to contact with a bearing plate 22 and the bolt E is provided with a stop pin 35 adapted to contact with another bearing plate 22.

The relative length of the bolts D and E 10 is not important, it being essential only that their respective arms 23 and 24 be located at such point as to be in operative position with respect to the location of the actuating member 19.

15 It will be noted that when the machine base B is in a raised position, as for example, that indicated in full lines in Figure 3, and is then lowered to its operative position as indicated in dotted lines in Figure 3, the locking 20 device will operate automatically; that is to say, the base latch 10 will engage the bar 8 on the bib C and the actuating member 19 will spread apart the bars D and E so that their respective outer ends will lock in and 25 engage the under surface of the table. All the parts will thus be firmly locked together in operative position and will remain so locked until such time as the actuating member 17 is manually operated against the tension of the spring 14 to cause the hooked part 12 to become disengaged or unlatched from the bar 8. Then and then only may the machine be swung out of its operative position, thereby withdrawing the actuating member 30 19 from between the arms 23 and 24 and permitting the springs 30 and 32 to expand and move the bolts D and E to their normal positions.

It will be noted that the locking functions 40 are performed simultaneously, but that before the unlocking of the bib C from the table A may be accomplished, it will first be necessary to unlock the machine B from the bib C. This inter-relation of the two locking parts 45 contributes to the utility of the device as a whole in machines of the character described, in that great steadiness and firmness is produced and vibration greatly reduced. Furthermore, this arrangement prevents damage 50 to the cabinet resulting from the operator attempting to lift the machine base from the bib without first properly unlocking the machine base lock.

I claim as my invention:

55 1. A device of the class described, comprising a fixed support and a movable support hinged thereto, a base member hinged to said fixed support and having means adapted to interlock with said movable support, a pair 60 of bolt bars mounted on the movable support adjacent that longitudinal margin opposite the hinged margin, said bolt bars being movable in opposite directions and adapted to engage the fixed support, and means rigidly secured adjacent the free margin of the base

member in position to automatically actuate said bolt bars when said base member is moved into juxtaposition to said movable support.

2. A device comprising a fixed support 70 having two independently movable elements oppositely hinged thereto, a pair of bolt bars movably mounted upon one hinged element near that longitudinal margin opposite the hinged margin, said bolt bars being movable 75 in opposite directions and adapted to engage the fixed support, and means rigidly secured to the free margin of the other hinged element in position to automatically actuate said bolt bars when said second hinged element 80 is moved into juxtaposition to said first hinged member, said bolt bars being provided on their proximate ends with bent arms parallel to each other, and said actuating means being provided with tapered surfaces for engaging said arms.

3. A disappearing-instrument cabinet comprising a fixed support having two independently movable elements oppositely hinged thereto, a pair of bolt bars movably 90 mounted upon one hinged element near that longitudinal margin opposite the hinged margin, said bolt bars being movable in opposite directions and adapted to engage the fixed support, means rigidly secured to the 95 free margin of the other hinged element in position to automatically actuate said bolt bars when said second hinged element is moved into juxtaposition to said first hinged member, said bolt bars being provided with 100 means for retracting the bars from latching engagement with the fixed support when the bolt bar actuating means is withdrawn, and means for locking said oppositely hinged members together.

4. In a drop head sewing machine cabinet, a fixed support, a support hinged to said fixed support, a machine base hinged to said fixed support and having means adapted to interlock with said hinged support, a pair of 110 spaced apart bolt bars movably mounted on the underside of said hinged support and having their proximate ends bent outwardly to project beyond the free margin of said hinged support, the other ends of said bolt bars being adapted to engage said fixed support, and means rigidly secured to the underside of the machine base in position to contact with said projecting bolt arms to automatically spread them apart when said machine base is lowered to the plane of said hinged support.

5. A device of the class described, comprising a fixed support and a movable support, a member hinged to said fixed support 125 and having means adapted to interlock with said movable support, and means operable by the movement of said member to interlocking position for interlocking said fixed and movable supports.

6. A disappearing - instrument cabinet, comprising a fixed support and a support hinged to said fixed support, an instrument base hinged to said fixed support and having means adapted to interlock with said hinged support, normally inoperative means carried by said hinged support and adapted to interlock with said fixed support, and means car-

ried by said instrument base for automatically actuating said last mentioned means prior to the interlocking of said instrument base and hinged support. 10

In testimony, that I claim the foregoing as my invention I affix my signature this 1st day of July, 1925.

WALTER ADAM SMITH.
